UNITED STATES PATENT OFFICE.

WILLIAM H. BAKER, OF CENTRAL FALLS, RHODE ISLAND, AND FREDERIC E. KIP, OF MONTCLAIR, NEW JERSEY.

LOOM.

SPECIFICATION forming part of Letters Patent No. 655,643, dated August 7, 1900.

Application filed November 3, 1899. Serial No. 735,646. (No model.)

To all whom it may concern:

Be it known that we, WILLIAM H. BAKER, residing at Central Falls, Providence county, Rhode Island, and FREDERIC E. KIP, residing at Montclair, Essex county, New Jersey, citizens of the United States, have invented certain new and useful Improvements in Looms, of which the following is a specification.

This invention relates to the class of looms which employ a series of shuttles for supplying to the web as required weft of different colors or kinds—such as box-looms, for example; and has for its object to supply full shuttles carrying weft of the several colors or kinds used in the weaving as the weft of a particular kind is exhausted.

In the accompanying drawings, which illustrate an embodiment of the invention, Figure 1 is a side elevation of the loom. Fig. 1^a is a plan of the magazine detent; and Fig. 2 is a front view of the side thereof seen in Fig. 1—that is, the right-hand side. Fig. 3 is a plan view of the shuttle-placer detached. Fig. 4 is a view similar to Fig. 1, but showing the shuttle-placer in operation. Fig. 4^a is a detached detail view of the detaining device for the placer. Fig. 5 is a plan view showing the shuttle-box and a shuttle therein on a larger scale than the principal views and including a diagrammatical view of the box motion and circuit connections. Fig. 6 is a vertical cross-section of the shuttle-box, showing how the contacts thereon are placed. Fig. 7 is an enlarged fragmentary sectional view of the shuttle, showing the circuit closer and breaker therein. Fig. 8 is a side view of the shuttle, on a smaller scale, showing the two side contacts. Figs. 9, 10, and 11 illustrate another electrical controlling device. Fig. 9 is a diagrammatical plan view, Fig. 10 is a side view of the shuttle on the same scale as Fig. 9, and Fig. 11 is an enlarged sectional view of the shuttle.

a represents the loom-frame, and *b* the breast-beam forming a part thereof.

c is the reed; *d*, the lay; *e*, the lay-swords; *f*, the crank-shaft; *g*, the connecting-rods which operate the lay.

h is the cam-shaft from which the picker-stick *i* is actuated, and *j* represents gear-

wheels through which the shaft *f* drives the shaft *h*.

All of the above parts are or may be constructed in a known manner.

On the lay is mounted a vibratable shuttle-box *k*. As herein shown, this box is open at the bottom and hinged or pivoted above, at *l*, in brackets *m* on the lay *e*. It is adapted to be swung outward, Fig. 4, toward the rear and is returned automatically by a suitable spring *n*. In suitable brackets *o* on the breast-beam or loom-frame is secured a series or set of upright magazines to contain shuttles *p*, carrying weft of different kinds or colors, and for convenience of description these have been supposed to contain shuttles filled with weft of different colors and have been indicated by letters *q^R*, *q^B*, *q^G*, and *q^W* to distinguish them as containing "red" weft, "blue" weft, "green" weft, and "white" weft, respectively. These magazines are grouped together, as clearly shown in Fig. 4, where they are represented in vertical transverse section. They may be conveniently considered as one magazine having a plurality of compartments, each compartment open at the bottom to deliver shuttles by gravity one by one into a shuttle-placer *r*, having four pockets or compartments which occupy positions under the respective magazines normally or when the placer is situated as in Fig. 1. The placer *r* is coupled to the upper longer arm *s* of a placer-lever fulcrumed at *t* on the loom-frame, and it is provided with a suitable retracting-spring *u*. If the lower shorter arm *v* of the placer-lever be pressed toward the front of the loom, the placer *r* will be moved rearward or toward the lay, and if the lay be at this time beat up the placer *r* will move over the lay, displacing the shuttle-box *k* laterally by swinging it about its point of suspension, Fig. 4. The extent to which the arm *v* of the placer-lever is pressed forward determines the particular pocket of the placer that will be thus brought into the place of the shuttle-box on the lay, and one means of operating the placer under electrical control is clearly shown in Figs. 1 and 4. On a lever *w*, suspended on the loom-frame back of the placer-lever, are mounted

at suitable intervals four electromagnets x^R , x^B , x^G , and x^W , and these may be considered as the controlling-magnets of the shuttle-magazines q , bearing, respectively, the same 5 letters—that is to say, the “red” magnet, the “blue” magnet, the “green” magnet, and the “white” magnet. Pivotally mounted on the lever w are the several armature-levers y of the respective electromagnets. The lay or 10 lay-sword carries four “daggers” or tappets z , which are so placed that when a particular magnet is excited and the armature-lever thereof is attracted and elevated the lever thus elevated will be alined in the path of 15 the tappet z opposite and corresponding thereto, so that when the lay beats up the tappet will impinge upon that armature-lever and swing forward the lever w , causing the lower free end thereof to strike the lower arm 20 v of the placer-lever and rock said lever in a manner to move the placer forward to an extent dependent on the particular armature-lever which shall have been encountered. In Fig. 4 the magnet x^G is represented as 25 excited, and consequently the cell of the placer r , which receives shuttles from the magazine q^G , has been brought to the proper position on the lay to be picked by the picker-stick i .

The cells of the placer r , as represented in 30 plan in Fig. 3, have been lettered in this view R, B, G, and W for convenience of reference. The placer is guided at its edges in the walls of the compound magazine, and it may have a spring buffer or cushion 2 on its front end, 35 where it impinges on the shuttle-box k for displacing the latter. To keep the shuttles from falling out of the open bottoms of the several magazine-compartments when the placer shall move out from under them, a 40 spring stop device is employed. This device is seen *in situ* in Figs. 1 and 4 and detached in Fig. 1^a. It consists of a sort of sliding grid 3, mounted in guides or ways just above the top of the placer and has a series of four 45 beveled bars 4, which normally rest under the respective walls or partitions of the magazine-compartments, as in Fig. 1; but this grid is backed by a spring 5, which tends to press the bars 4 wedge-like under the piles 50 of superposed shuttles in the magazine-compartments to support the shuttle; but when the placer r is returned to its normal position under the magazine, Fig. 1, a clip or clips 6 on the end of the placer engage and press 55 back the grid 3, so as to permit the shuttles to descend into the placer.

Controlling means are provided whereby when a shuttle-carrying weft of a particular color becomes nearly exhausted it will on entering the shuttle-box k complete an electric circuit through the particular electromagnet which corresponds to that color in the shuttle, and we will now describe the preferred manner of effecting this end or purpose on a 60 box-loom.

The shuttle p , Figs. 7 and 8, has hinged in it a spindle 7, and it has fixed in the outer

face of one of its sides, Fig. 8, two contact-plates 8 and 9. The plate 8 is electrically connected in any convenient manner with a 70 spring-contact breaker 10, and the plate 9 is electrically connected in any convenient manner within the shuttle with a contact pin or piece 11 in the shuttle, and normally when the shuttle is empty the spring 10 will be in 75 contact with said pin 11, so as to close the circuit between the contact-plates 8 and 9. When, however, a bobbin 12 is slipped down over the spindle 7, the free end of the spring 10 enters a slot 13 in the bobbin at its butt, 80 and the overwound weft thereon, crossing the said slot, bears on an outwardly bent or curved portion of the spring 10 and presses the latter inward, thus moving it out of contact with the pin 11, so as to break the circuit between the plates 8 and 9. As shown in Fig. 7, the spring 10 is fixed in the body of the shuttle at one end and is loosely coupled to the head of the pivotally-mounted spindle, so that it flexes and follows the latter. The coupling may be simply an eye or keeper on the head of the spindle, through which the spring plays rather loosely. When the shuttle enters the box k , the plates 8 and 9 thereon come into contact with spring-contact terminals 13 and 14, respectively, on the box. One of these terminals is seen in Fig. 6. These contacts 13 and 14 are terminals of an electric circuit including a generator 15, Fig. 5, a conductor 16, with branches 17 90 through the coils of the respective electromagnets x and terminating in a series of contact-terminals 18, situated near the box-motion 19 at the opposite side of the loom, and a return-conductor 20, which has a terminal 100 21 on the lifting-rod 22 of the box-motion 19. It may be well here to explain that when the box-motion 19 is operated by the usual mechanism to bring a shuttle-carrying weft of a certain color up or down to the raceway the terminal 21 of the return moves up or down with it and is thus made to close the circuit through a particular magnet x . For illustrative purposes merely we have 105 marked the shuttle-boxes in the box-motion, 110 shown in Fig. 5, R, B, G, and W, so as to agree with these letters on the electromagnets in order that it may be readily seen that a shuttle with green weft is at the raceway or “in play” and that the circuit is closed by the 115 terminal 21 through the green magnet x^G . If under these conditions the weft in the green shuttle in play shall become nearly exhausted or sufficiently so to allow the spring 10 to come into electrical contact with the pin, 120 piece, or part 11, and this shuttle shall enter the box k , such entry will complete the circuit through the magnet x^G , the current will flow from the generator 15 to the terminal 21, thence to the branch 17, which leads to the 125 magnet x^G , thence by conductor 16 to the spring-contact 13 on the shuttle-box, thence to the plate 8 on the shuttle, Figs. 7 and 8, thence to the spring 10, thence to the pin 11, 130

thence to the plate 9, thence to the spring-terminal 14 on the box, and thence back to the generator by conductor 20. The magnet x^g will be excited and will attract its armature-lever y , and on the beat-up of the lay the pocket (G in Fig. 3) of the placer r , which pocket contains a full green shuttle p , will be brought into position on the lay for picking.

As the lay is in its beating-up position when 10 the placer moves to the position over the lay (seen in Fig. 4) and must move back to the position for picking it through the warp-shed before the picker acts, obviously the placer must move back with it. Hence means are 15 provided for detaining the placer and coupling it to the lay until it is released by the picker-stick. This detainer is in the form of a pawl and ratchet. On the under side of the placer are four beveled teeth 23, one for each pocket 20 in the placer and so situated as to respectively engage a spring lever-pawl 24, carried by the lay. When the placer is moved out over the lay until one of its pockets is over the latter, the proper tooth 23 engages the 25 pawl 24, and as the lay moves back the placer is necessarily carried with it, the placer-lever s yielding. When the proper point is reached, the picker-stick strikes and passes entirely through the placer-pocket lengthwise. 30 As it passes clear of the placer a lateral stud 25 on the stick (seen in Fig. 2) rides under the long arm of the lever-pawl 36 and by rocking it releases the placer. The spring u then returns the latter to its normal position 35 of rest. Obviously the varied extent of movement of the placer over the beat-up lay is attained by the tappets z , acting on the pendant lever w at different distances from its fulcrum or point of suspension.

40 In Figs. 5 to 8 we have shown a means for the electrical selection of the color of the weft through the operation of the box-motion 19 of the loom, and have also shown a shuttle wherein the circuit making and breaking device is mounted in the shuttle and entirely disconnected from the bobbin; but it will be obvious that we may employ other constructions for effecting these objects—as, for example, those illustrated in our United States 45 Patent No. 636,707, dated November 7, 1899. In this construction the selection of the color of the weft is effected by having special shuttles for each color, or special in so far that the contact-plates on the sides of the shuttles 50 are set so as to close the circuit, each through its particular electromagnet, the magnets being in branch circuits. The shuttle instead of having its circuit breaker and closer on the shuttle has it carried by the bobbin. These 55 constructions are illustrated in Figs. 9, 10, and 11 and will now be briefly described. The conductor 26 of the circuit includes the generator 15 and has branches 27, which lead to the several electromagnets x^R , x^B , x^G , and 60 x^W . From these magnets these branches lead to as many spring-contact terminals 28 on the shuttle-box k . The shuttles p , as in-

dicated by full and dotted lines in Fig. 10, will have their contact-plates 29 so placed as to contact when the shuttle is in the box with 70 the particular terminal 28 required—that is to say, a shuttle carrying blue weft with the branch leading to the magnet x^B and one with a white weft with the branch leading to magnet x^W , as in Fig. 9. The shuttle seen 75 in Fig. 11 shows the contact-spring 30 held out of contact with the contact-band 31 by the overwrapped weft, both contacts being on and carried by the bobbin precisely as illustrated in our pending patent before mentioned. As the shuttle-box is to be swung to one side by the placer it is desirable that the spring-contact terminals thereon shall be so mounted as to adapt themselves to this movement. Hence we prefer to employ the 80 construction shown clearly in Fig. 6. The contact (13 in this figure) is secured to the side of the box k and insulated, and it has an upward spring branch or extension 32, which bears on the hinge-axis 33 of the shuttle-box, 85 or, preferably, on a metal collar 34 thereon, the conductor 16 being connected electrically with this collar. The collar may be insulated from the hinge-axis. This construction allows the box to be rocked without disturbing 90 the contact of the branch 32 with the collar 34. When the shuttle-box is rocked and displaced, it throws out the empty shuttle, and this latter may be received in any kind of 95 tray or receptacle, as 35. (Seen in Figs. 1 100 and 4.)

The detainer has been described as a simple pawl-and-ratchet device, consisting of a pawl 24, engaging the teeth 23 on the placer and adapted to be displaced by a lateral stud 105 25 on the picker-stick; but in the specific construction which we prefer to employ and which is seen detached in Fig. 4^a the pawl 24 is not formed integrally with the operating-lever 36, but connected therewith by a link 110 37. This construction, however, is only adopted for convenience. Any arrangement which will detain the placer and which will free it at the proper time may be employed. Fig. 2 shows the spring 38, which holds the 115 pawl in engagement with the teeth on the placer.

To make clear the extent and scope of the present invention, we would state that in our United States Patent No. 636,705, dated 120 November 7, 1899, we show means for supplying a loom, such as a box-loom, with shuttles bearing weft or filling of different colors or kinds, and we do not claim, broadly, this feature of the invention; nor do we limit ourselves to it, as the other features of this invention are adapted to a weft-supplying mechanism where only one magazine is employed. It may also be stated that in our United States Patent No. 637,695, dated November 21, 1899, 125 130 we show means for supplying a loom with filled shuttles wherein a placer is employed in connection with a vibrating shuttle-box; but in this construction both the placer and

the shuttle-box are actuated by a rotating cam in the loom. In the present application the shuttle-box is not operated independently of the placer and the latter is actuated by the 5 lay or other vibrating point of the loom.

An important feature of this invention consists in providing a box-motion loom with means for supplying it automatically with weft or filling of different kinds or colors, as 10 may be required and selected, electrical means for setting in operation said weft or filling supplying mechanism, said electrical means being controlled by the presence or absence of weft or filling in the shuttle, and 15 an electrical switch device or selecting device whereby the shifting of the box-motion according to the requirements of the pattern serves to select and determine what particular kind or color of weft or filling shall be 20 supplied to the loom, and being the first, as we believe, to accomplish a result of this kind with the aid of electricity we claim such electrical selection and control broadly.

Having thus described our invention, we 25 claim—

1. In a loom, the combination with a vibratable, swinging shuttle-box, and a magazine to contain filled shuttles, of a vibratable placer, adapted to swing the shuttle-box to 30 one side by its impact thereon, and also to receive the shuttles from the magazine and carry them to the picking position, and means for vibrating said placer at proper times.

2. In a loom, the combination with a laterally-vibratable, swinging shuttle-box, a spring 35 which returns said box to its normal position, and a shuttle-magazine, of a vibratable placer to transfer the shuttles from the magazine, said placer being adapted to swing and dis- 40 place the shuttle-box sidewise by its impact thereon, and means for vibrating said placer at proper times.

3. In a loom, the combination with a shuttle-magazine, of a vibratable placer to take a 45 shuttle from the magazine and carry it to the picking-point, a detainer for holding said placer at the picking position until the shuttle of the placer has been picked, means for operating the placer at proper times, means 50 for releasing the latter when its shuttle has been picked, and a laterally-swinging shuttle-box, adapted to be displaced by and to make room for the placer.

4. In a loom, the combination with a shuttle-magazine, of a vibratable placer to take a 55 shuttle from the magazine and carry it to the picking-point, a detainer for holding said placer in its position at the picking-point until the shuttle held therein has been picked, the 60 picker-stick, means for operating the placer at proper times, means actuated by the picking operation for releasing the latter when its shuttle has been picked, and a swinging shuttle-box adapted to be displaced by the 65 impact of the placer, to make room for the latter.

5. In a loom, the combination with a shut-

tle-magazine, and a vibratable placer for carrying a shuttle from the magazine to the picking-point, of a detainer for holding the placer 70 at the picking-point until the shuttle therein has been picked, means for operating the placer at proper times, mechanism for picking the shuttle, means whereby the placer is released by the picking mechanism at the end 75 of the picking operation, and a vibratable shuttle-box adapted to be displaced to make room for the placer.

6. In a loom, the combination with the lay, and a shuttle-magazine, of a vibratable placer 80 to take a shuttle from the magazine and carry it to the lay, a detainer for holding said placer in its position on the lay until the shuttle of the placer has been picked, means for operating the placer at proper times, the picker-stick, means whereby said stick releases the placer through the picking operation, and a vibratable shuttle-box adapted to be displaced to make room for the placer.

7. In a loom, the combination with the lay, 90 the swinging, vibratable shuttle-box thereon, and a spring or springs for returning said box to place, of the vibrating placer adapted to displace or swing aside said shuttle-box by impact thereon.

8. In a loom, the combination with the lay, the vibratable shuttle-box thereon, and a shuttle-magazine, of a vibratable placer, adapted to transfer a shuttle from the magazine to the lay and to displace at the same 100 time the said shuttle-box, mechanism between the lay and said placer whereby the former operates the latter at proper times, and electrical means controlling the times of operation of the said intermediate mechanism, said 105 electrical means being set in operation by the exhaustion or partial exhaustion of the weft or filling in the shuttle in play.

9. In a loom, the combination with the lay and a displaceable shuttle-box thereon, of a 110 series of magazines or compartments for holding carriers of different kinds of weft or filling, a vibratable placer having a series of 115 pockets to receive weft-carriers from the respective magazines or compartments and carry them to the lay, means for operating said placer and shuttle-box, and electrical means for determining the extent of movement of said placer toward the lay, said electrical means being set in operation by the exhaustion or partial exhaustion of the weft or 120 filling on the weft-carrier in play.

10. In a loom, the combination with the lay and a displaceable shuttle-box thereon, of a 125 series of magazines or compartments for holding carriers of different kinds of weft or filling, a vibratable placer having a series of 130 pockets to receive weft-carriers from the respective magazines or compartments and carry them to the lay, means for operating said placer and shuttle-box, and electrical means for determining the extent of movement of said placer toward the lay, said electrical means including a normally-open cir-

cuit which is held open or closed by the presence or absence of weft or filling in the shuttle in play.

11. In a loom, the combination with the lay 5 and a displaceable shuttle-box thereon, of a series of magazines or compartments for holding carriers of different kinds of weft or filling, a vibratable placer having a series of pockets to receive weft-carriers from the 10 respective magazines or compartments and carry them to the lay, means for operating said placer and shuttle-box, and electrical means for determining the extent of movement of said placer toward the lay, said electrical 15 means including a normally-open circuit which is held open or closed by the presence or absence of weft or filling in the shuttle in play, the circuit being completed by the entry of the shuttle into the said vibratable 20 shuttle-box.

12. In a loom, the combination with the vibrating lay, and the shiftable shuttle-box mounted thereon, of a magazine having a series of compartments situated at different 25 distances from the lay, a placer *r*, mounted slidably under said magazine and having a series of pockets corresponding to the several compartments of the magazine, means for operating said placer to advance it over the 30 lay, and means for setting in operation at proper times the mechanism which operates said placer.

13. In a loom, the combination with the vibrating lay, the shiftable shuttle-box on the 35 lay, and the stationary magazine having a series of compartments situated at different distances from the lay, of a placer *r*, slidably mounted under said magazine and having a series of pockets corresponding respectively 40 to the several compartments of the magazine, means for operating said placer, means for detaining it when moved out over the lay, means for releasing the placer, and electrical means for setting in operation the placer-operating mechanism at proper times.

14. In a loom, the combination with the vibrating lay, the shiftable shuttle-box on the lay, and the stationary magazine having a series of compartments situated at different 50 distances from the lay, of a placer *r*, slidably mounted under said magazine and having a series of pockets corresponding respectively to the several compartments of the magazine, means for operating said placer, means for detaining it when moved out over the lay, means for releasing the placer, electrical means for setting in operation the placer-operating mechanism at proper times, and for controlling the extent of movement of the 55 placer.

15. In a box-loom, the combination with the vibrating lay, a shiftable, single shuttle-box *k* mounted thereon at one side of the loom, a box-motion 19, at the opposite side 60 of the loom, and a magazine with shuttle-compartments at that side of the loom where the box *k* is situated, of the placer *r*, mech-

anism for operating the placer, electrical means, set in operation by the entry of the shuttle in play into the box *k*, for setting in 70 operation the placer-actuating mechanism, and a switch device, actuated by the box-motion, which determines the extent of movement of the placer.

16. In a loom, the combination with the lay, 75 the magazine having a series of compartments, the vibratable placer under the magazine, and means for moving said placer out over the lay, said means comprising a lever *s*, a lever *w*, a series of electromagnets 80 mounted on the lever *w* at different distances from its fulcrum, the armature-levers of said magnets, and a series of tappets *z*, moving with the lay, the said tappets and magnets corresponding in number to the pockets in 85 the placer, of an open electric circuit having branches including said magnets, and terminals at a shiftable shuttle-box on the lay, the said box, means carried by the several shuttles whereby exhaustion of the weft on the 90 shuttle in play closes said circuit on the entry of the shuttle into the said box, and means substantially as described for selecting and switching in the proper magnets.

17. In a loom, the combination with the lay, 95 of the shuttle-box *k*, suspended thereon, the contact 13, mounted on the box and provided with a branch 32, which bears on a terminal at the hinge-axis, the said terminal, and a shuttle having a contact-plate on its face 100 which forms a rubbing contact with the contact 13 when the shuttle enters the box.

18. In a loom, the combination with the vibrating lay, the box-motion 19 at one side of the loom, the shuttle-box *k*, at the other side 105 of the loom, means for supplying shuttles carrying weft of the various kinds to replace those exhausted, and electrical controlling means comprising a series of magnets, an open electric circuit having branches including the respective magnets, said circuit having terminals at the shuttle-box whereat the circuit is completed by the entry of an exhausted shuttle into said box, and a selecting-switch 21, operated by the box-motion to 110 switch in the proper magnet, substantially as set forth.

19. In a weft-supply mechanism for looms, the combination with the lay, the box-motion and the shuttle-box at the side of the 120 loom opposite to the box-motion, of an electric circuit having branches 17 containing each an electromagnet and having a terminal 18, and the main circuit having terminals at the shuttle-box and a terminal 21, carried by the box-movement, whereby the shifting of the boxes of the box-movement serves to put the proper magnet in circuit, substantially as set forth.

20. A shuttle provided with a hinged spindle, exterior contact-plates 8 and 9, a contact-breaking spring 10, set in the shuttle-body and connected electrically with one of said contact-plates, and a pin or piece 11, con-

5 nected electrically with the other of said contact-plates, the parts 10 and 11 being normally in contact, in combination with a bobbin or holder for weft or filling, adapted to fit on said spindle and having in it a slot to receive the free end of the spring 10 when said holder is in place on the spindle.

21. A shuttle provided with a hinged spindle, exterior contact-plates 8 and 9, a contact-breaking spring 10, set in the shuttle-body and connected electrically with one of said contact-plates, a pin or piece 11, connected with the other of said contacts, and means for connecting the spring 10 to the spindle so 15 that it may flex and follow the spindle when the latter is opened out, the parts 10 and 11 being normally in contact, in combination with a bobbin or holder for weft or filling, adapted to fit on said spindle and having in it a slot to receive the free end of the spring 10 when said holder is in place on the spindle.

22. A box-motion loom having the following instrumentalities, namely, means for automatically supplying weft or filling of different kinds or colors as required, electrical means for setting in motion said supplying mechanism, said means being controlled by the presence or absence of weft or filling in the shuttle, and electrical selecting means, 25 controlled by the box-motion of the loom, whereby the shifting of the box-motion determines the kind or color of weft or filling to be supplied.

23. In a loom, the combination with a shift-35 able shuttle-box situated at one side of the loom, a box-motion situated at the other side of the loom, and a magazine having shuttle-compartments to contain shuttles carrying different kinds or colors of weft or filling, of 40 a shuttle-placer having a plurality of pockets corresponding and pertaining to the respective compartments in the magazine, and means for moving said placer to the picking-point of the loom to furnish a fresh supply 45 of weft or filling of the kind or color substantially exhausted in the shuttle in play.

24. In a loom, the combination with a shift-able shuttle-box situated at one side of the loom, a box-motion situated at the other side 50 thereof, and a magazine having a plurality of shuttle-compartments to contain shuttles carrying weft or filling of different colors or kinds, of a shuttle-placer having a plurality of shuttle-pockets corresponding and per-55 taining to the respective compartments of the magazine, and means for operating said placer and controlling the times of its movements to the picking-point of the loom to furnish a fresh supply of weft or filling of the color or 60 kind being used by the shuttle in play, said

means consisting of an electromagnet and an electric circuit including said magnet, said circuit being held open by the presence and adapted to be closed by the substantial absence of the weft or filling in the shuttle in 65 play.

25. In a loom, the combination with a shift-able shuttle-box situated at one side of the loom, a box-motion situated at the other side thereof, and a magazine having a plurality 70 of shuttle-compartments to contain shuttles carrying weft or filling of different colors or kinds, of a shuttle-placer having a plurality of pockets corresponding and pertaining to the respective compartments in the magazine, 75 means for operating said placer and shuttle-box, and electrical means for determining the kind or color of weft or filling which is to be placed in position to be picked through the warp-shed, said electrical means being set in 80 operation by the exhaustion, or partial exhaustion of the weft or filling in the shuttle in play.

26. In a loom, the combination with a shift-able shuttle-box situated at one side of the 85 loom, a box-motion, situated at the other side thereof, and a magazine having a plurality of shuttle-compartments to contain shuttles carrying weft or filling of different kinds or colors, of a shuttle-placer having a plurality 90 of pockets corresponding and pertaining to the respective compartments in the magazine, means for operating said placer and shuttle-box, and electrical means for determining the color or kind of weft or filling which is to be 95 placed in position to be picked through the warp-shed, said electrical means including a circuit which is held open or closed by the presence or absence of the weft or filling in the shuttle in play.

27. In a loom, the combination with the box-motion, and the shuttle-box at the side of the loom opposite to the box-motion, of an electric circuit having terminals at the shuttle-box, and a plurality of branches correspond-105 ing in number to the boxes in the box-motion, an electromagnet in each of said branches, and a switch device controlled by the box-motion and adapted to switch into the circuit the respective magnets as it is shifted, sub-110 stantially as set forth.

In witness whereof we have hereunto signed our names, this 25th day of August, 1899, in the presence of two subscribing witnesses.

WILLIAM H. BAKER.
FREDERIC E. KIP.
